UNITED STATES PATENT OFFICE

GOLLADAY LAKE, OF GRENADA, MISSISSIPPI

CIGAR AND CIGARETTE HOLDER

Application filed March 18, 1928, Serial No. 261,383. Renewed February 7, 1931.

The present invention relates to cigar and cigarette holders, and aims to provide a cigar or cigarette holder of simple and inexpensive construction, which will enable the cigar or cigarette to be conveniently smoked, and which obtains advantages over the ordinary cigar and cigarette holders in prevailing use.

It is the object to provide a novel mouthpiece for holding a cigar or cigarette which will provide for the free passage of smoke into the mouth, without obstruction, and without the smoke passages being apt to be stopped up. Furthermore, the mouth end of the cigar or cigarette is kept dry, and nicotine will not collect in the mouthpiece, the mouthpiece having an outlet opening so arranged as to provide for a full smoke outlet and for free drainage. The improved mouthpiece is also less apt to become strong and discolored, as compared with the ordinary mouthpiece in use heretofore, and the holder or mouthpiece also eliminates or reduces other objections.

The invention is illustrated in the accompanying drawings, wherein—

Figure 1 is a plan view of a cigarette holder or mouthpiece constructed in accordance with the present invention.

Fig. 2 is a longitudinal section thereof, on the line 2—2 of Fig. 1, showing same in position in the mouth.

Fig. 3 is a side elevation of a cigar holder made in accordance with the invention.

The holder or mouthpiece comprises a socket or bowl portion 7 and a biting portion 8, the latter being held between the teeth, as seen in Fig. 2, and the portion 7 having a socket or bowl 9 to receive the end of the cigar or cigarette in the usual manner.

In the ordinary mouthpiece heretofore in prevailing use, the socket 9 opens, with a reduced outlet, through the rear end of the mouthpiece, but in carrying out the present invention, the rear end of the mouthpiece is closed, and the biting portion 8 has an opening 10 therethrough transversely of the axis of the mouthpiece. As shown, the biting portion 8 is relatively flat and the opening 10 is vertical, being in the upper and lower surfaces of the portion 8. The socket or bowl

9 extends at its rear end to the opening 10, thereby providing a large smoke outlet whereby the smoke may pass from the socket 9 through the opening 10 without restriction, to keep the rear end of the cigar or cigarette dry, and to permit for free drainage from the socket. The lips embrace the mouthpiece in front of the opening 10, as seen in Fig. 2. The opening 10 being large will also enable the socket and opening to be kept clean and free of nicotine, to prevent staining or discoloring of the lips and fingers.

The mouthpiece or holder may be made of a celluloid compound or any other suitable material, and is inexpensively manufactured. The device may be readily molded.

The improvements may be embodied in different types of mouthpieces, including smoking pipes, within the scope of what is hereinafter claimed.

Having thus described the invention, what is claimed as new is:—

A cigar or cigarette mouthpiece having a socket and a flat biting portion closed at the rear end and provided with a large vertical opening of uniform size through its biting portion beyond and in communication with the rear end of said socket, said opening being of larger area than the rear end of said socket and extending forwardly and rearwardly beyond the point of said biting portion which the teeth are intended to engage.

In testimony whereof I hereunto affix my signature.
